UNITED STATES PATENT OFFICE.

FRANKLIN R. ROBISON, OF GLOVERSVILLE, NEW YORK, ASSIGNOR TO ASHER MANUFACTURING COMPANY, OF IRVINGTON, NEW JERSEY, A CORPORATION OF NEW JERSEY.

CLOTHES-RETURN DEVICE FOR IRONERS.

Application filed September 12, 1922. Serial No. 587,802.

To all whom it may concern:

Be it known that I, FRANKLIN R. ROBISON, a citizen of the United States, residing at Gloversville, Fulton County, New York, have invented certain new and useful Improvements in Clothes-Return Devices for Ironers, of which the following is a specification.

The present invention relates to a clothes return device adapted to be associated with automatic ironing machines of the type wherein the pieces to be ironed are fed in at one side of the machine and delivered at the opposite side.

15 The principal object of the invention is to provide an improved and simplified device to facilitate the return from the delivery to the feeding side of the ironing machine, of pieces that must be passed through the 20 machine more than once.

At the present time, many laundries are doing family washes by the "no mark" or individual bundle method. According to this method the family washes are run through 25 the machine individually one after the other. The heavier pieces, usually, must be run through the ironer a second time in order to thoroughly dry them. Usually the heavy pieces of each wash are run through the ironer first, and then these pieces are returned 30 to the feeding side of the machine to be run through again, the lighter pieces being passed through the machine between the first and second runs of the heavier pieces. The

35 present invention comprehends a device for returning the heavy pieces from the delivery to the feeding side of the machine. Heretofore, in some instances, mechanical means have been employed for so transferring the

40 heavy pieces. One form of device consists of a chute running from the delivery to the feeding side of the ironer into which the clothes are thrown at the delivery side and slide through the chute to the feeding side.

45 In another form of device, an endless belt conveyer is employed for this purpose. This conveyer extends under the ironing machine, takes power to operate and delivers the clothes to the feeding end in more or less wrinkled condition. This is also true of the

50 chute method so that the operator at the feeding end of the ironer is obliged to straighten out these returned pieces before they can be again passed through the ma-

chine. Furthermore, the conveyer type of device in some instances returns the clothes to the feed trough at the feeding side of the ironer and it frequently happens that the operator forgets to take these clothes out of the trough and feed them to the ironer, with the result that the pieces of the various washes become mixed. It has been proposed to provide a return conveyer disposed over the top of the ironer. This is objectionable, however, for the reason that such a conveyer will interfere with the free escape of vapors from the machine with the result that the efficiency of the ironer will be lowered.

The present invention comprehends a return clothes device adapted to be applied to ironers already constructed or to new ironers. Essentially it comprises a carrier mounted for reciprocal movement, at the will of the operator, from one side of the ironer to the other.

In its present preferred form the device consists of a trough-like receptacle which extends the full width of the ironer and is mounted to be swung, at the will of the operator, from one side of the ironer to the other. When the heavy pieces, which must be run through the ironer more than once, are being ironed, the carrier is moved to the delivery side of the machine into position to receive the pieces as they are discharged. The arrangement is such that the pieces collect in the carrier unrinkled, in the form of accordion pleating. After all the heavy pieces forming part of the mixed singled family wash have been received in this manner, the conveyer is moved out of the way of the operator at the delivery side and the light pieces that require only one passage through the ironer are operated on. After all these light pieces have been fed into the ironer, the laden carrier is moved to the feeding end of the ironer and the operator takes the heavy pieces therefrom and again feeds them into the ironer. As the pieces have automatically folded themselves into the carrier, scarcely any labor is required to remove them from the carrier and insert them at the feeding end of the ironer. In the form of the invention described herein, the carrier is mounted to swing from an overhead position alternately to either the delivery or feeding side of the ironer.

Other objects and features of novelty will

be apparent from the description taken in connection with the drawings in which:

Figure 1 is a more or less diagrammatic side elevation of one embodiment of the invention shown associated with one type of ironing machine;

Figure 2 is an elevation of part of the delivery side of the ironer with the device attached thereto; and

Figure 3 is a perspective view of a detail illustrating part of the brake mechanism.

In the drawings, there is shown, as much of a well-known ironing machine as is necessary to illustrate the application of this invention thereto, it being understood that this particular machine is shown merely for the purpose of illustration. The invention is applicable to ironing machines of the general type wherein the pieces to be ironed are fed in at one side and discharged at the other.

Referring to the drawings, the numeral 1 indicates one of the side frames of the ironing machine which rotatably support the cylinder 2, the various rollers which carry the endless apron 3 and other parts of the ironer. The pieces to be ironed are placed in a feeding trough or receptacle 4 from which they are taken by the operators and placed upon the feed tapes 5 of the ironing machine from whence they pass between the apron and cylinder. The pieces are carried down between the cylinder and apron in a counterclockwise direction as viewed in Figure 1, and travel around almost the full circumference of the cylinder to the point 6, where the pieces are doffed from the cylinder and taken around the roller 7 and on to the upper run of apron 3 to the discharge point 8 whence they drop onto the table 9. The operators are usually stationed at both sides of the machine, some to feed the articles to the ironer and others to fold and remove the pieces from the delivery table 9.

As previously stated, with the individual bundle method, it is necessary to keep the pieces of the individual washes together. Some of these pieces, however, are so heavy that they will not be dried by one passage through the ironer. The present invention comprehends means for transferring pieces from the delivery side to the feeding side of the ironer. In the embodiment of the invention illustrated, a carrier in the form of a shallow receptacle 10 is mounted for movement to the position 10^a at the delivery side of the ironer where it is in position to receive the pieces as they are delivered from the apron. In falling from the points 8 into the carrier, the pieces automatically fold themselves in the form of accordion pleating so that there is no wrinkling or crumpling of the pieces. After all of the heavy pieces have been received in the car-

rier in this manner, the carrier is moved out of the way of the operator to a position such as illustrated in full lines in Figure 1. The thinner pieces of the particular wash are then fed through the ironer and after all of these have been supplied to the machine, the carrier 10 is moved to position 10^b shown in dotted lines at the feeding side of the ironer. The operators then take the heavy pieces from the carrier and feed them to the machine for a second passage therethrough. As the pieces in the carrier are folded and unwrinkled, it is an easy matter for the operators to take them from the carrier and place them on the feeding tapes 5 of the ironer. After all of the pieces have been fed from the carrier, it is moved away from the feeding side of the ironer and other washes are started through the machine.

One method of mounting the carrier is illustrated in the drawings, this being at the present time the preferred construction. As shown, a shaft 11 is rotatively mounted at the top of the ironer substantially parallel to the axis of the cylinder 2, being carried in bearing blocks 15 mounted on brackets 16 secured to the side frames 1. Rigidly secured to this shaft 11 are a pair of spaced arms 14 from the ends of which is suspended the carrier 10. This may be accomplished by providing the carrier at its ends with bales 12 pivotally secured to the lower ends of links 13 which in turn are pivoted to the arms 14 adjacent the free ends thereof. For a purpose presently to be described the arms adjacent their free ends are provided with a plurality of spaced holes 14^a in any one of which the bolt 13^a may be placed for pivotally securing the links 13 to the arms 14. It is desired to counterbalance the carrier 10 so that it will normally occupy a position such as illustrated in full lines in Figure 1 or the dotted line position indicated at 50 in Figure 1. For this purpose a weight 18 is provided carried by the arm 17 secured to the shaft 11, this weight being positioned diametrically opposite the arms 14. Preferably this weight slightly more than counterbalances the receptacle 10 and its supporting parts, so that when the receptacle is loaded, the weight, with the aid of a push from the operator, will move the carrier from the position 10^a to the full line position shown in Figure 1.

Means is provided to hold the carrier in any desired position. In the form of the invention shown this is accomplished by means of a brake normally applied to prevent rotation of the shaft 11. Thus a drum 22 is rigidly secured to the shaft 11 at one end of the ironer and a band 23 passes around the same, one end of this band being fixed to a bracket 25 secured to the standard 16 and the other end being secured to a

lever 24 pivoted on a pin 26^a carried by the angle piece 26 secured to the bracket 25. Means is provided for normally applying the brake. For this purpose in the form 5 of the invention shown a weight 24^a is mounted at the free end of the brake lever 24. For the purpose of permitting an operator at either side of the machine to release the brake, treadles 28 and 29 extending the 10 full width of the machine are provided, the treadle 28 being carried by a plurality of arms on a rock shaft 30. The outer of these arms shown at 30^a is in the form of a lever and extends to the opposite side of the rock 15 shaft 30 and at its free end is pivotally connected as at 27^a to the lower end of a link 27, the upper end of which is pivotally connected to the brake arm 24 as at 27^b. If desired, this brake arm may be provided 20 with a plurality of apertures 24^b to adjustably receive the upper end of this link 27. The other treadle 29 is carried on a plurality of arms on a rock shaft 31, the end arm 31^a extending by the shaft 31 and constituting 25 a lever, the inner end of which is provided with a slot 31^b receiving the pivot pin 27^d, thus connecting levers 31^a and 30^a to the lower end of link 27. Thus when either 30 of the treadles 28 or 29 is depressed, the brake arm 24 will be raised releasing the 35 brake and permitting movement of the carrier 10. Although a specific type of brake mechanism has been described, it is to be understood that other forms of devices might be employed for controlling the movement of the carrier.

For the purpose of permitting the carrier 40 to be pulled from its overhead position to either side of the ironer, flexible connections such as indicated at 19 and 20 may be provided, the connection 20 being secured to the upper end of one of the arms 14 and passing around an overhead pulley 21. The connection 19 is secured to the free end of one of 45 the arms 14 and passes around an overhead pulley 21^a from whence it depends to a position accessible to the operator at the delivery side of the ironer.

In the operation of the device, usually the 50 carrier occupies an overhead position such as illustrated in full lines in Figure 1, being held in this position by the weight 18 and the normally applied brake. When the operator at the delivery side of the ironer desires 55 to lower the carrier for the purpose of receiving the heavy pieces which must be run through the ironer a second time, she steps on the treadle 28, thereby releasing the brake, and then she grasps the carrier 10 and pulls it down to the dotted line position 60 10^a. If the carrier had been in the position illustrated in dotted lines at 50, she would have first pulled the carrier to her side of the machine by the flexible connection 19. After the carrier has been moved to the posi-

tion 10^a, the treadle is released whereupon the brake is applied, to hold the carrier in this position. It is now in place to receive the pieces as they are delivered from the ironer. The rollers 40 and 41 of the ironing machine are adjustable horizontally to the right to take up slack in the apron so that the carrier 10 should also be adjustable to the right. The various apertures 14^a in the arms 14 are provided for this purpose. After all the heavier pieces of the individual wash have passed through the ironer and folded themselves in the carrier 10, the operator releases the brake whereupon the weight 18 raises the carrier to the full line 70 position shown in Figure 1. If the weight is not heavy enough to accomplish this, the operator gives the carrier a slight upward 75 push. The operator at the feeding side of the machine continues to feed in the light pieces of the wash and after these have all been fed to the ironer, she steps on the treadle 29 thereby releasing the brake and by pulling on the flexible connection 20 80 swings the carrier 10 to her side of the ironer where she can pull it down to the position 10^b. When the carrier has assumed this 85 position, the treadle 29 is released whereupon the brake automatically applies itself and holds the carrier against displacement. 90 The heavier pieces are now taken from the carrier 10 and fed through the ironer for a second time. After all of these heavy pieces have been supplied to the ironer, the operator steps on the treadle 29 whereupon the 95 100 brake is released and the carrier automatically swings to the dotted line position 50.

Although the invention has been described in detail, it is to be understood that it is not limited to the exact construction shown but includes modifications and changes which come within the scope of the appended 105 claims.

Having thus described my invention what I claim as new and desire to secure by Letters Patent is:

1. The combination with an ironer, of a device for transferring clothes from one side of the ironer to the other, including a pivoted support extending above the ironer and a carrier freely suspended from said support.

2. The combination with an ironer, of a device for transferring clothes from one side of the ironer to the other, including an arm pivoted on a transverse axis and extending above the ironer, and a carrier freely suspended from the outer end of said arm on an axis parallel to the pivotal axis thereof.

3. The combination with an ironing machine having feed and delivery sides, of a carrier, and means supporting said carrier so that it may be swung over the machine and down into positions adjacent said feed

4
and delivery sides, and manually controlled means for holding said carrier in any position to which it may be moved and for swinging said carrier to either side of the machine.

4. The combination with an ironing machine of the kind described, of a carrier, means supporting said carrier so that it may be swung over the machine and to either side thereof, a brake for holding the carrier in any position to which it may be moved, and means for releasing said brake operable from either side of said machine.

5. The combination with an ironing machine of the kind described, of a carrier, means supporting said carrier so that it may be swung over the machine and down on either side thereof, means on either side of the machine for swinging said carrier to that side, a normally applied brake for holding the carrier in any position, and means for releasing said brake operable from either side of the machine.

6. The combination with an ironing machine of the kind described, of a carrier, a transverse shaft journaled above the machine, parallel arms rigid with said shaft, links suspending said carrier from the outer ends of said arms so that said carrier may swing between said arms, a weight rigid with said shaft for counterbalancing said carrier, normally applied means for holding said shaft against rotation, and means operable from either side of the machine for releasing said means.

7. The combination with an ironing machine of the kind described, of a carrier extending along the width of the machine,

parallel arms pivoted to the frame of the machine to turn about a transverse axis, 40 links suspending said carrier from the outer ends of said arms so that said carrier may swing between said arms from one side of the machine to the other, normally applied means for holding said arms in any position, 45 and means operable from either side of the machine for releasing said means.

8. The combination with an ironing machine of the kind described, of a carrier extending along the width of the machine, 50 parallel arms pivoted to the frame of the machine to turn about a transverse axis, links suspending said carrier from the outer ends of said arms so that said carrier may swing between said arms from one side of the machine to the other, and manually controlled means for operating said arms to swing said carrier to either side of the machine at the will of the operators on the respective sides.

9. The combination with an ironing machine of the kind described, of a carrier, parallel arms pivoted to the frame of the machine to turn about a transverse axis, 65 links suspending said carrier from the outer ends of said arms so that said carrier may swing between said arms from one side of the machine to the other, manually controlled means for operating said arms, 70 means tending to hold said arms in any position, and means operable from either side of the machine for releasing said holding means.

In testimony whereof I hereunto affix my signature.

FRANKLIN R. ROBISON
